BENDING MACHINE TO FORM WIRE ARTICLES CONTAINING AN OFFSET

John C. Bertram, Mayville, N. Y., assignor to Bertram Wire Products, Inc., Buffalo, N. Y.

Application November 1, 1956, Serial No. 619,854

7 Claims. (Cl. 153—34)

This invention relates generally to the wire forming art, and more particularly to a new and useful means for forming wire articles having an offset bight portion with a compound bend therein.

Heretofore, when forming wire articles having an offset bight portion with a bend therein, it has been the practice to resort to separate forming operations. For example, the article might be initially formed with all the parts thereof lying in a common plane, and then finally formed to the desired shape by separate bending and/or offsetting operations. This practice requires multiple handling, increases the likelihood of rejects, and in these and other ways greatly increases the cost of such articles.

Accordingly, it is a primary object of this invention to provide a mechanism for forming, in one operation, wire articles having offset bight portions with compound bends therein.

Another object of this invention is to provide a mechanism which will accomplish the foregoing without stretching and thereby weakening the wire.

A wire forming device constructed in accord with my invention is characterized by the provision of die means having a face portion corresponding to the curvature of the desired bight portion when projected on a base plane, first forming tool means movable toward the face portion of said die to bend a length of wire therearound and initially form such bight portion in that base plane, die parts offset from the base plane and corresponding to the offset curvature desired in such bight portion including any bend therein, additional forming tool means movable to draw the bight portion of such wire out of its base plane and against the die parts while the wire is held against the die means, and means for so moving the additional forming tool means following predetermined movement of said first forming tool means.

The foregoing and other objects, advantages and characterizing features of a wire forming mechanism constructed in accord with my invention will become clearly apparent from the ensuing detailed description of a presently preferred embodiment thereof, taken together with the accompanying drawings illustrating such embodiment wherein like reference numerals represent like parts throughout the various views and:

Fig. 1 is a plan view of a wire forming mechanism constructed in accord with my invention showing the retracted position of the forming tools in full lines and the extended, forming position thereof in broken lines;

Fig. 1A is a fragmentary, somewhat schematic detail view illustrating the operation of one of the forming tools thereof;

Fig. 1B is a fragmentary, somewhat schematic detail view illustrating the wire holding action between the forming tool of Fig. 1A and the die, being taken about on line 1B—1B of Fig. 1;

Fig. 2 is a sectional view taken about on line II—II of Fig. 3;

Fig. 3 is a view partly in section and partly in elevation, being taken about on line III—III of Fig. 2;

2

Fig. 4 is an elevational view taken about on line IV—IV of Fig. 1;

Fig. 5 is a plan view of a wire article formed by the mechanism of Figs. 1 through 4;

Fig. 6 is a sectional view thereof taken about on line VI—VI of Fig. 5;

Fig. 7 is a perspective view showing the article of Figs. 5 and 6 incorporated in a guard for a trouble lamp; and

Fig. 8 is a generally diagrammatic, isometric view of the mechanism of Fig. 1.

A wire forming mechanism constructed in accord with my invention is adapted to form wire into any of a wide number and variety of finished products, as will become obvious. For illustrative purposes only, and without thought of limitation, there is shown in Figs. 1—4 of the accompanying drawing and described hereafter die and forming tool parts designed and arranged in accord with my invention to produce the article illustrated in Figs. 5 and 6 and comprising a horseshoe, generally designated 1, adapted to be secured to a hinge 2 and a vertical rib 3 to comprise therewith the wire guard of, for example, a trouble lamp indicated in broken lines at 5.

It will be seen from Figs. 5, 6, 7 that the horseshoe 1 comprises a length of wire stock bent to form a tapered pair of side leg portions 6 having at one end thereof inwardly and upwardly inclined terminals 7 and joined at their other end by a bight portion bent upwardly out of the plane of side leg portions 6 and comprising upwardly and inwardly curving portions 8 and an interposed compound bend 9.

Heretofore, when forming the horseshoe 1 it was the practice to initially bend a length of wire to form a bight portion, side leg portions and terminals all lying in a common plane, and then by separate operations to form the upturned terminals 7 and the offset bight portion and bend 9 therein.

However, with a machine constructed in accord with my invention a length of wire is formed into the finished shape illustrated in Figs. 5—7 in a single operation, thereby greatly facilitating the manufacture of such articles and reducing the expense thereof.

In the wire forming device of my invention shown in Figs. 1—4, there are provided a fixed die and a number of forming tools movable relative thereto and coacting therewith in a manner to be described. The die and forming tools are mounted on a conventional wire forming machine of a type known in the art, such as for example the automatic four slide wire forming machine made by the Baird Machine Co. of Stratford, Conn., which in itself is no part of my invention and the details of which are not essential to an understanding of the invention. For these reasons, the machine proper is only suggested in the drawing by ways, slides and a few other parts adjacent the die and forming tools.

Thus, the machine proper will have provided as a part thereof an arm-like extension 11 terminating at its outer end in a generally U-shaped bracket 12 to which the stationary forming tool, hereinafter referred to as the die, is attached by means of a die plate 13, the latter being secured to bracket 12 as by bolts 14 or the like. A block 15 is positioned above plate 13, and the die includes a main body part 16 and a bottom plate 17 therebelow, with bottom plate 17 being secured to main body part 16, and main body part 16 and block 15 being secured to plate 13, as by bolts or the like indicated at 18.

The main die body 16 is provided with an enlarged head fitting into a recess in the bottom of plate 13 and providing overhanging shoulders 20 along the opposite sides of said die body 16. The front face 19 of body part 16 and the side walls 21 thereof beneath shoulders 20 are shaped to provide the plan view outline of bight

portion 8, 9 and side leg portions 6 as illustrated in Fig. 5.

In operation, a supply of wire 22 is fed into the machine across the front face 19 of the die by a conventional wire feeding mechanism, part of which is indicated at 23', and the desired, predetermined length 22' thereof is cut off by a conventional wire cutter 23 as it is held against the die by a front first forming tool unit generally designated 24. Front tool 24 comprises a pair of opposed jaw parts 25 spaced apart a distance equal to the width of the bight portion of the article being formed, comprising the maximum width of the die body part 16, each of said parts 25 having generally semicircular grooved front faces 26 adapted to engage the cut wire 22' and urge it against the front face 19 of die part 16 and then bend the same therearound. The inner side faces of said parts 25 are elongated and have a generally horizontal ledge or shelf portion 27 adapted to underlie the side leg portions 6 of the wire and, together with the cooperating overhanging shoulders 20 of the die body 16, to hold said length of wire in place against the die 16 (Fig. 1B).

Each front forming tool part 25 is provided with a transverse first depending flange 28 abutting against the front wall of a forming tool holder plate 29, and adjacent its rear edge with a second depending flange 30 fitting in a groove in the holder plate 29, thereby securing the forming tool part 25 against lengthwise movement relative to holder plate 29. Forming tool parts 25 are releasably secured to holder plate 29 as by bolts 32 extending through transversely elongated slots 33 in the tool parts 25, whereby the spacing between the opposed jaws of tool parts 25 can be selectively adjusted.

Holder plate 29 is mounted on a front slide 35, being secured thereto as by a bolt 36 extending through a lengthwise elongated slot 37 in holder plate 29, to permit selective axial positional adjustment of the holder plate relative to its slide. Slide 35 is slidable in a way 38 and has an upstanding portion 39 comprising a bearing for a set screw 40 which bears against a pad plate 41 at the back of holder plate 29, whereby set screw 40 can be manipulated to axially adjust the position of holder plate 29 in way 38. Plate 29 then is locked in position by the bolt 36 and set screw 40, the latter being held by a lock nut 45.

It will be appreciated that slide 35 is a standard forming slide and is operated in a conventional manner as by a standard cam, not illustrated. In operation, after a length of wire 22 is fed across the front face 19 of die part 16, the front forming tool 24 is moved inwardly in the direction of the arrow 42, and as it bears against the wire 22 and holds it in place against die 16 the cutter 23 automatically severs the wire to its correct length 22'. The movement of cutter 23 is synchronized with that of tool 24 in any desired manner, as by securing the cutter to holder 29.

The front forming tool 24 continues its inward movement and bends the wire piece 22' around the front face portion 19 of die part 16, as illustrated in Fig. 1A, and then along the sides thereof between the overhanging shoulders 20 on the die and the ledges 27 on the forming tool. However, the front forming tool does not bend the side leg portions 6 against the die in a manner to taper the same, but leaves them extending straight back.

A feature of particular importance in a wire forming device of this invention is the forming of the offset bight portion and the compound bend therein during the single forming operation on the wire piece 22', and in the device illustrated in Figs. 1-4 this is accomplished in the following manner. The overhanging shouldered portions 20 on the die part 16 extend around the front face 19 thereof, and are provided at the front face with upwardly curving undersurfaces 43 (Fig. 3) corresponding to the desired curvature of bight portions 8. Also, die

body 16 has a forwardly extending part 44 on the top center of its front face, which extension has an under surface corresponding to the curvature of bend 9 in the bight portion. Second forming tools comprising a pair of generally L-shaped, bellcrank levers 45 are pivoted on die part 16, one on each side of extension 44, for movement about a transverse axis relative to die part 16, as by means of pivot pins 46. Each lever 45 includes a relatively long upstanding leg 47 movable in slots formed in die body 16, die plate 13 and block 15, and a relatively short leg 48 movable in slots in die part 16 and adapted to engage beneath the wire piece 22' at front face 19 and draw it up against the shoulder surfaces 43 and around extension 44 on opposite sides thereof to produce the compound bend, offset bight portion 8, 9 illustrated in Figs. 5-7.

A block 49, undercut to accommodate front tool parts 25, is secured to the front forming tool holder plate 29 as by bolts or the like, and resilient biasing means such as a pair of coil springs 50 are secured at one end to the outer ends of legs 47 of levers 45 and at their other ends to anchor terminals 51 secured to block 49 as by bolts 52. Springs 50 thereby normally urge the levers 45 in a counterclockwise direction as viewed in Fig. 2, whereby both legs thereof are out of the path of movement of wire 22 as it is fed into the machine.

A second forming tool actuator part 53 is slidable in a groove in block 49, being adjustably positioned therein as by a set screw 54 carried in a bearing plate 55 on the back of the block 49. Actuator part 53 is locked in adjusted position as by a bolt 56 extending through an axially elongated slot 57 therein, whereby it is movable with the front forming tool 24 as a part thereof, being positioned between the front tool parts 25.

In operation, the length of wire 22' is partially bent around the front face of the die body 16 by the forming tool parts 25 to the extent necessary to hold the wire piece against the die part 16, whereupon the actuator part 53 bears against the legs 47 of levers 45 and urges them in a clockwise direction as viewed in Fig. 2 against the action of springs 50 causing the legs 48 thereof to swing upwardly and thereby draw the previously flat bight portion of the wire piece 22' against the under surface 43 of the forward shouldered portions 20 and around the bottom of the extension 44, to provide the curving offset and compound bending comprising portions 8 and 9.

Thus, the compound bend, three dimensional form of the article bight portion is produced in one operation, as distinguished from the multiple operations previously required, by virtue of the above described arrangement for initially partially bending a length of wire to form side leg portions and a bight portion lying in a common plane and then drawing the bight portion out of the plane of the side legs and against die parts producing the compound bend therein as forming of the side legs continues.

The forming tool ledges 27 and overhanging die shoulders 20 cooperate to receive the side leg portions 6 of the wire 22', as indicated in Fig. 1B, and hold the wire against die body 16 with a degree of tightness sufficient to produce such bending of the bight but without clamping it in a manner such that the wire would be stretched and thereby weakened. In other words, the shoulders 20 and ledges 27 hold the wire on opposite sides of the bight portion sufficiently tightly to enable parts 45 to draw the wire upwardly as described above while permitting motion of the wire relative thereto to provide the additional wire required for such forming without stretching the wire. This is of extreme significance, because wire loses its strength when stretched, and solves the problem of avoiding stretching which heretofore necessitated separate forming operations.

Then, the side leg portions 6 are bent against the sides of die part 16, to provide the tapered form of the finished

article 1, and terminals 7 are bent inwardly, this being accomplished as by means of side forming tools 60 which are carried on slides 61 in ways 62 in a manner similar to the front forming tools 24, being secured on the slides as by bolts 63 extending through transversely elongated slots 64 in the tools.

Each side tool 60 is provided with a projection 65 extending forwardly of a flat, obliquely directed portion 66 which latter engages the side leg portions 6 at approximately the juncture thereof with the terminals 7 to hold the same against the sides of die body 16 while the projections 65 bend the terminals 7 inwardly, as illustrated in Fig. 1.

Then the inwardly extending terminals 7 are bent upwardly out of the plane of side leg portions 6 as by a rear or back forming tool 70 which is secured to a slide 71 in a way 72 as by a bolt 73 extending through a transversely elongated slot 74 in the tool. Tool 70 preferably includes at its forward end a pair of rollers 75 aligned with terminals 7 and journaled for rotation about substantially horizontal axes positioned below the plane of side leg portions 6, whereby as back tool 70 is moved inwardly toward the die, rollers 75 engage beneath terminals 7 and bend the same upwardly. Rollers 75 are used because they are not subject to as much wear as for example a fixed wedge would be.

It will be noted that each of side tools 60 and back tool 70 is provided with a recessed or notched formation 60' and 70', respectively, interlocking with corresponding formations on the slides 61 and 71, respectively, to prevent relative axial movement therebetween.

While these various forming steps occur sequentially in the manner described above, it will be appreciated that they occur in very rapid order and comprise but a single operation producing a completely formed article without further handling. This operation is summarized as follows.

At the beginning of each cycle of operation wire stock is fed across the front face 19 of die body part 16 and is cut off as the front forming tool 24 is caused to move in and bend the length of wire 22' therearound. After front forming tool 24 has moved through approximately one-third of its movement, enough to hold the wire 22' sufficiently tightly to permit drawing of the bight portion, the actuator part 53 on front tool 24 bears against levers 45 carried by the die and swings them up to draw the bight portion upwardly against shoulders 20 and extension 43 to produce the offset and compound bend therein, as forming tool 24 continues its inward movement. This occupies approximately one-half the total operating time in each cycle, and the front forming tool 24 then holds the partially formed article in position on die 16. Meanwhile side tools 60 have been moving in and they then bend the wire side leg portions against the sides of the die and bend the terminals 7 inwardly while continuing to hold the side leg portions 6 against the die body part 16, this action occupying approximately the succeeding one-quarter of each cycle. Meanwhile the back tool 70 has been moving in and it then engages beneath terminals 7 and bends them upwardly during the remainder of the cycle. All of the forming tools then are withdrawn simultaneously and the completed article 1 is removed from the die, with the device automatically continuing this cyclic operation as long as the machine is running.

Thus, my invention fully accomplishes the above objects. While the device specifically disclosed herein uses die and tool parts shaped and arranged to form the illustrated horseshoe 1, it is obvious that other shapes and arrangements can be used to produce articles of different form and that the same is susceptible of other variations, all without departing from the spirit of the invention and the scope of the appended claims.

Having fully disclosed my invention in a presently

preferred embodiment thereof, and described its mode of operation, what I claim as new is:

1. In a device for forming a wire article having a portion offset from a plane and formed with a bend therein, first die means having a face portion shaped to provide the plan view curvature of such wire article portion, first forming tool means movable toward said first die means to initially bend a length of wire around said face portion in said plane, second die means positioned on one side of said plane and shaped to provide the curvature of such bend, third die means positioned on said one side of said plane on opposite sides of said second die means and shaped to provide the desired offset curvature on opposite sides of such bend, second forming tool means movable into engagement with such wire on the opposite side of said plane and on opposite sides of said second die means to draw such wire out of said plane and against said second and third die means, and means for so moving said second forming tool means.

2. A device for forming a wire article of generally U-shaped plan view form having opposite side leg portions lying in a common plane, an offset bight portion, and inturned terminals bent out of said plane, said device comprising, die means having a face portion and opposite side portions shaped to provide the plan view outline of such article, first forming tool means movable toward said face portion to bend a length of wire therearound and thereby initially form such bight portion and opposite side leg portions in a common plane, die parts extending from said face portion on one side of said plane and shaped to provide the desired offset of such bight portion, second forming tool means movable to engage such initially formed bight portion from the other side of said plane and draw the same against said die parts, third forming tool means movable toward said die side portions for engaging such side leg portions and bending the terminals thereof inwardly, and fourth forming tool means movable toward such inturned terminals to bend the same out of said plane.

3. A device as set forth in claim 2, wherein said die side portions taper from said face portion, with said first forming tool means initially forming such side leg portions in generally parallel relation, and said third forming tool means bending such initially formed side leg portions against said die side portions to provide the desired taper thereof.

4. A device as set forth in claim 2, wherein said fourth tool means comprise roller means journaled about an axis transverse to such side leg portions and offset from said plane.

5. In a device for forming a wire article having an offset portion with a bend therein, die means having a face portion, means for feeding a length of wire into position adjacent said face portion, forming tool means movable toward said face portion to bend such length of wire therearound and thereby produce a preliminary forming thereof in a common plane, said die means including a part offset from said plane on one side of such length of wire, movable lever means arranged to engage such length of wire on the other side thereof and draw the same out of said plane and against said die part, and means for so moving said lever means following predetermined movement of said forming tool means toward said die means, said forming tool means holding such length of wire against said die means with a degree of tightness enabling such drawing thereof by said lever means without stretching the wire, wherein said lever means comprise a bell crank type of lever having angularly related leg portions, and means movable with said forming tool means for engaging one leg portion and thereby pivoting said lever to cause the other leg portion thereof to engage such wire and draw the same out of said plane against said die part.

6. In a device for forming a wire article having an offset portion with a bend therein, die means having a

face portion, means for feeding a length of wire into position adjacent said face portion, forming tool means movable toward said face portion to bend such length of wire therearound and thereby produce a preliminary forming thereof in a common plane, said die means including a part offset from said plane on one side of such length of wire, movable lever means arranged to engage such length of wire on the other side thereof and draw the same out of said plane and against said die part, and means for so moving said lever means following predetermined movement of said forming tool means toward said die means, said forming tool means holding such length of wire against said die means with a degree of tightness enabling such drawing thereof by said lever means without stretching the wire, wherein said lever means comprise a pair of bell crank type levers positioned on opposite sides of said die part, spring means biasing the wire engaging legs of said levers out of wire engaging position, and means carried by said forming tool means for engaging the other legs of said levers and urging the wire engaging legs thereof into wire engaging position.

7. In a device for forming a wire article having an offset intermediate portion with a bend therein and opposite side portions adjacent thereto, die means having a face portion, means for feeding a length of wire into position adjacent said face portion, forming tool means movable toward said face portion to bend such length of wire therearound and thereby produce a preliminary forming thereof into intermediate and side portions lying in a common plane, said die means including a part offset from said plane on one side of the intermediate portion of such

length of wire, movable lever means arranged to engage the intermediate portion of such length of wire on the other side thereof and draw the same out of said plane and against said die part to offset such intermediate portion and produce the desired bend therein, and means for so moving said lever means following predetermined movement of said forming tool means toward said die means, said forming tool means holding the opposite side portions of such length of wire against said die means with a degree of tightness enabling such drawing thereof by said lever means without stretching the wire, wherein said die means have shoulder forming parts on one side of said plane, and said forming tool means have shoulder forming parts opposed to said die shoulder parts on the opposite side of said plane, said die and forming tool shouldered parts cooperating to hold such wire against said die while permitting the passage of wire therebetween to provide the additional length of wire required by such drawing operation.
